United States Patent Office

Des. 196,480
Patented Oct. 1, 1963

196,480

LAWN SPRINKLER

Graham Fee and William E. Portz, Geneva, Ohio,
assignors to True Temper Corporation, Cleveland,
Ohio, a corporation of Ohio

Filed Nov. 6, 1962, Ser. No. 72,405

Term of patent 14 years

(Cl. D91—1)

FIGURE 1 is a front perspective view of a lawn sprinkler showing our new design;

FIGURE 2 is a rear perspective view thereof; FIGURE 3 is a bottom view of a section of the end plate shown at the left end of FIGURE 1.

The dominant features of our design reside in the portion shown in solid lines.

We claim:

The ornamental design for a lawn sprinkler, as shown and described.
